UNITED STATES PATENT OFFICE.

ERNEST DAVIS, OF SYRACUSE, NEW YORK, ASSIGNOR TO THE PROSPERITY COMPANY, INC., OF SYRACUSE, NEW YORK, A CORPORATION OF NEW YORK.

PRESSING-MACHINE ELEMENT.

Application filed October 5, 1926. Serial No. 139,725.

This invention has for its object a particularly light pressing element for pressing machines, as the head or the buck of a pressing machine and particularly a sheet metal head or buck and means for distributing the heat throughout the ironing face of the head or the buck or both.

5

The invention consists in the novel features and in the combinations and constructions 10 hereinafter set forth and claimed.

In describing this invention, reference is had to the accompanying drawing in which like characters designate corresponding parts in all the views.

15 Figure 1 is a fragmentary side elevation partly in section of the type of pressing machine embodying my invention.

Figure 2 is a transverse sectional view through the pressing element provided in my 20 invention.

Figure 3 is an enlarged transverse sectional view.

Figure 4 is a plan view of the pressing element.

25 The pressing elements as the head and buck of laundry and garment pressing machines have heretofore been made of cast iron which distributes the heat substantially equally throughout the ironing face and also on account of its volume retains as well as distributes the heat. Also, such cast iron bucks or heads are comparatively heavy and when one of them is movable it requires heavy counterweights. The counterweights as well as the 30 heavy heads necessarily cause the machine to operate slowly.

35 This invention relates to a light movable pressing element or head so that the weight of the head and also that of the counterweights 40 or springs is reduced and the machine has a quick snappy action in opening and closing rather than a slow cumbersome action.

I have here shown my invention as embodied in a machine in which the upper pressing element or head is movable toward and from the lower element or buck and is carried at the front end of the yoke or lever having a counterbalancing weight at its rear end.

45 1 designates the head movable toward and from a buck 2 mounted on a goose neck 3, which in turn is carried by a suitable frame 4.

50 5 is the yoke or lever pivoted at 6 between its ends to a standard 7 rising from the frame 4 and carrying the head 1 at its front end and a counterweight 8 at its rear end. As will

be understood by those skilled in the art, the actuating mechanism is also connected to the rear end or arm of the lever 5. The head 1 is formed up of sheet metal and as sheet metal does not retain heat and does not distribute 60 the heat quickly but on the contrary, a sheet metal buck would ordinarily be hot in spots, means is provided for quickly and evenly distributing the heat from a circulating heating medium throughout the ironing face of the 65 head.

70 The head comprises a hollow body and has a wall 9 on one side thereof provided with an ironing or pressing face 10, and usually the upper portion of the head or the body thereof, that is, the portion including the top and the side walls is stamped from one blank and the wall 9 from another blank and the top portion and the wall 9 are secured together in any suitable manner as by welding. Thus, the 75 buck 1 is formed with a heating chamber directly above the wall 9. Means is provided for distributing a heating medium over the inner face of the wall 9 so that the outer or pressing face 10 will be evenly heated.

80 In the illustrated embodiment of my invention, the walls of this heating chamber opposite the wall 9 is formed with a plurality of passages for the heating medium, these passages being distributed throughout the length 85 and breadth of the heating chamber, and automatic means is provided for controlling the opening and closing of the passages. This automatic means comprises normally-open, thermostatically-operated valves controlled 90 by the heat within the heating chamber above the wall 9.

95 As here illustrated, the interior of the buck 1 is divided by a partition 11 into upper and lower chambers 12 and 13 and this partition is formed with a plurality of passages 14 therethrough. Also, the upper chamber 12 is provided with an inlet 15 for a heating medium as air or steam and the lower chamber 13 with an outlet 16. The inlet 15 opens 100 through the top of the chamber 12 centrally thereof and a deflector 17 is located within the chamber 12 opposite the inlet 15.

105 The thermostatically operated valves for controlling the passages 14 are here shown as disk shaped heads 18 which are connected by a stem 19 to a thermostatic element that is, a thermostatic element here shown as a dished bimetallic disk 20. When the disk 20 becomes heated, it warps or distorts 110

in one direction to close the corresponding passage 14.

The heating medium preferably air is circulated through the chambers by means of a pump 21 mounted on the yoke lever 5 and having its inlet pipe 22 connected to the outlet 16 of the chamber and having its outlet 23 connected to the inlet 15 of the chamber 12. The air is heated while being circulated, and as here shown it is heated in the outlet pipe 23 of the pump by an electrically heated heat generator 24. Any other suitable form of heating means may however be provided. In order that the sheet metal body may retain the heat, it is lined or partly lined with a heat retaining layer of asbestos material 25.

In operation, assuming that the head is cold, all of the valves 18 will be open. Upon the starting of the pump 21 the air passes through the pipe 23 into the chamber 12, it being heated while so passing through the pipe 23. From the chamber 12, it passes through the open passages 14 throughout the chamber 13. However, on account of the nature of sheet metal, the wall 9 thereof will be hotter in some spots than in others. The valves located in the hotter portions of the chamber will expand and close the corresponding passages 14 so that the most of the heating medium will pass to the cooler portions until the heat is evenly distributed throughout the wall 9.

This invention is particularly advantageous in that it allows a light sheet metal buck to be used instead of the heavy cast iron heads requiring large counterweights and heavy supports which sheet metal buck can be readily and quickly heated throughout its ironing face.

What I claim is:—

1. A hollow pressing element for pressing machines having a heating chamber, one wall of which is formed with a pressing face, means for circulating a heating medium throughout the heating chamber and thermostatically controlled valve means within the chamber for distributing the heating medium over the wall of the chamber formed with the pressing face.

2. A pressing machine element having an internal chamber and means for circulating a heating medium through the chamber and a plurality of thermostatically operated valves in said circulating system for distributing the heating medium throughout the chamber, the valves being operable independently of each other.

3. A pressing machine element having an internal chamber and means for circulating a heating medium through the chamber and a plurality of thermostatically operated valves in said circulating system for distributing the heating medium throughout the chamber, the valves being operable inde-

pendently of each other, the thermostatic elements of the valves being located in contact with different portions of the wall of said chamber.

4. A pressing machine element comprising a hollow body enclosing a chamber having a wall on one side thereof provided with a pressing face, another wall of said chamber being provided with a plurality of inlets for a heating medium, means for circulating the heating medium through the said inlets and the chamber, and thermostatically controlled valves operable independently of each other for controlling the inlets.

5. A pressing machine element comprising a hollow body enclosing a chamber having a wall on one side thereof provided with a pressing face, another wall of said chamber being provided with a plurality of inlets for a heating medium, means for circulating the heating medium through the said inlets and the chamber, and thermostatically controlled valves operable independently of each other for controlling the inlets, the thermostatic elements of the valves being located in contact with the wall formed with the pressing face.

6. A pressing machine element comprising a hollow body enclosing a chamber having a wall on one side thereof provided with a pressing face, the opposite wall of said chamber being provided with a plurality of inlets for a heating medium, means for circulating a heating medium through the said inlets and the chamber, and thermostatically controlled valves operable independently of each other for controlling the inlets, said valves having their thermostatic elements in contact with the wall provided with the pressing face.

7. A pressing machine element comprising a hollow body one wall of which is provided with a pressing face, the hollow body having a heating chamber and said wall forming one side of the heating chamber and other walls of the heating chamber being formed with a plurality of passages distributed throughout the length and breadth of the heating chamber and thermostatically operated valves for controlling the flow of heating medium through said passages, the valves being operable independently of each other, the valves having their thermostatic elements located adjacent the wall of the body provided with the pressing face whereby said elements are controlled by the heat conducted from the portions of said wall in the localities of the thermostatic elements of said valves.

8. A pressing machine element comprising a hollow body having a wall on one side thereof provided with an outer pressing face, a partition within the body dividing it into two chambers, said partition extending in the same general direction as the wall which is provided with the pressing face, said partition being formed with a plurality of passages therethrough distributed over the area of

said partition and normally closed thermostatically operated valves for controlling the flow of a heating medium through said passages and means for passing said heating medium through said chambers and said passages.

9. A pressing machine element comprising a hollow body for receiving a heating medium, the wall on one side of the hollow body having a pressing face, a partition dividing the interior of the body into compartments, the partition extending in the same general direction as said wall and being formed with a plurality of passages therethrough distributed over the area of the partition and thermostatically operated means for controlling the flow of a heated medium through said passages, an inlet for the heating medium opening into one chamber, and an outlet leading from the other chamber.

10. A pressing machine element compris-

ing a hollow body one wall of which is provided with a pressing face, the hollow body having a heating chamber and said wall forming one side of the heating chamber and another wall of the heating chamber being formed with a plurality of passages distributed throughout the length and breadth of the heating chamber and thermostatically operated valves for controlling the flow of a heating medium through said passages.

11. A pressing element for pressing machines comprising a hollow metal body and thermostatic means within the body for distributing a heated medium throughout the pressing face of the body.

In testimony whereof, I have hereunto signed my name, at Syracuse, in the county of Onondaga, and in the State of New York, this 13th day of Sept., 1926.

ERNEST DAVIS.
